APPARATUS FOR CURING TOBACCO

Richard Crane and William J. Snadecki, Westover, Va.; said Snadecki assignor to said Crane

Application September 23, 1938, Serial No. 231,396

2 Claims. (Cl. 131—134)

Our invention relates to apparatus for curing tobacco, and more particularly to the general method known as "flue curing."

In the usual method of flue curing, the chamber, hereinafter referred to as "the barn", in which the tobacco leaves are hung in customary manner, is provided with brick flues heated by wood fuel to the proper temperature for curing.

The time required for heating these flues to 10 the curing temperature is a considerable item in the cost of curing, as wood must be supplied constantly, requiring the attendance of one or more according to conditions.

When the curing process is in operation, constant supervision is necessary to maintain a 15 curing temperature, removing part of the fuel when temperature is too high, and supplying wood as required, to vary the temperature at different stages of the curing operation. The replenishing of the fuel permits the escape of smoke into the atmosphere of the barn, and the tobacco leaves are impregnated and a recognized flavor is imparted to the tobacco which is considered as beneficial. It is obvious that the impregnation can not be uniform in different 20 batches cured, and depends on the skill of the operator and his judgment of the volume of escaping smoke.

As now managed, this process, including the 25 preheating of the flues, is unduly expensive, requiring an excess of wood fuel, constant supervision for several days, control of the curing temperature by primitive means, and no uniform means for controlling the volume of smoke admitted to the atmosphere of the curing barn.

One object of our invention is to provide apparatus which is economical in installation, and in operation, which will produce flue cured tobacco at a material reduction in cost of fuel, and the 30 reduction of the time required in supervision during the process and in the actual time elapsed in the curing process.

A second object is to provide apparatus of the character required, with means for maintaining 35 uniform temperature in the barn as required at different stages of the process, and means for controlling such temperatures and admission of the required volume of wood smoke to the atmosphere with a minimum of supervision.

Our invention consists in the novel arrangement of heat radiating members in connection 40 with the furnace, and controlling members for maintaining and varying temperatures, and for controlling admission of wood smoke to the atmosphere of the barn; also means for supplying

extra heat to cooler portions of the barn to maintain uniform temperatures at different stages of the curing operation.

Other novelties and advantages will appear in the accompanying specifications and claims, and illustrated in the drawing forming a part thereof.

In the drawing,

Fig. 1 shows a sectional elevation of a tobacco barn in which a preferred embodiment of our invention is installed.

Fig. 2 is a sectional plan, substantially on line 10 2—2, Fig. 1.

These figures are diagrammatic, obvious details being omitted.

Fig. 3 is a fragment in section, showing the 15 means for supplying wood fuel to the furnace, with a minimum escape of smoke.

Fig. 4 is a fragment in section, showing a 20 baffle plate by means of which each smoke flue is insured an equal volume of the products of combustion.

Fig. 5 is a plan view of a smoke vent and movable closure to control the volume of smoke admitted to the barn atmosphere.

In the drawing, 10 is the tobacco barn in which 25 the bunches of leaves are hung in the usual manner. The wood burning furnace 11 is of a type known as "air tight", and consists of a sheet iron body the body being raised above the floor by legs 12. An opening 13 in front is provided 30 with a closure hinged at 14, and formed as a hopper with the back 15 normally closing the opening 13, and the angularly disposed plate 16, on which logs of wood may be placed for feeding the fire. Arcuately formed sides 17, connect the 35 two plates, permitting the discharge of a log into the furnace with little escape of smoke, handles 18 being provided to enable the operator to swing the hopper on its hinges, discharge the log, and return to normal closed position. Suitable draft 40 dampers are provided as at 19, 20 to secure efficient combustion.

The products of combustion discharge through 45 opposite disposed ducts 21, 22, which are extended around within the walls of the barn, functioning as radiating surfaces, the ducts uniting above and within the door opening 23, in an uptake at 24, discharging above the roof as at 25.

The ducts 19, 20 are each provided with a damper 26, 27 by means of which the volume of 50 heated waste gases passing thereto, may be controlled, and the consequent radiation from the surfaces of the ducts, adjusted to vary the amount of heat according to the needs in different parts of the barn.

Depending within the furnace from the crown sheet, is a baffle plate 28 between the openings to the ducts to insure that each duct may have its full share of the products of combustion, and 5 radiate uniformly when full open.

The ducts are supported at suitable height from the floor of the barn and sufficient distance from the walls, on brackets 29, providing free working space within the line of ducts, for hanging and 10 inspecting the tobacco during the curing process.

Suitable air inlets 30 are provided near the floor, to admit fresh air to the barn as needed, and ventilators 31 are suitably placed to permit 15 escape of moist air. At suitable intervals we provide vents 32 through which smoke from the interior of the ducts may be admitted to the barn, shutters 33 being operative to vary the area of the openings to keep a uniform smoke content in the atmosphere and thus secure uniformity in the 20 flavor of the cured tobacco.

While we have shown the apparatus diagrammatically in Figs. 1 and 2, and the dampers and closures are shown as manually operated it is 25 obvious that known instruments in common use for similar controls, and automatic in action, may be employed instead of the manually operated members, to secure uniform results in different batches of tobacco.

As an auxiliary means for keeping the temperature uniform in all parts of the barn, we provide a duct 35 by means of which a current of 30 heated air may be directed toward a cool portion. This duct is swiveled at 36 to the top of a hood 37 forming a portion of the heater 10. Air is

admitted through openings 39 in the lower edge of the hood, to the interior where it is heated and flows outward through the duct which may be directed toward any portion of the barn that may require additional heat to preserve uniformity. 5

Having thus described our invention, we claim:

1. An apparatus for flue curing tobacco comprising a wood burning heater member, having a plurality of smoke flues extending therefrom and constituting heat radiator elements; an independent duct swiveled on the heater member top, formed as a hood and having openings permitting ingress of air above the crown sheet of the heater member, said air being free to pass through the swiveled duct; a baffle plate depending from the crown sheet of the heater member within the heater and between the outlets to the smoke flues; means for controlling the rate of combustion of fuel and means for permitting a regulated volume of smoke to pass into the atmosphere of the barn in which the apparatus is installed. 10

2. In an apparatus of the character described in claim 1, means for supplying wood fuel to the heater member, comprising a closure formed with an extended apron and arcuate side plates connecting the closure and apron, forming a hopper hinged below the feed opening of the heater member, and adapted to receive a log, and swing it into the firepot with a minimum of 15 20 25 30 escaping smoke therefrom.
